[57] CLAIM

The ornamental design for a miniature battery-operated light, as shown and described.

DESCRIPTION

FIG. 1 is a perspective view of a miniature battery-operated light embodying my new design.

FIG. 2 is a front elevational view thereof.

FIG. 3 is a side elevational view thereof, the opposite side being a mirror image thereof.

FIG. 4 is a top plan view thereof.

FIG. 5 is a bottom plan view thereof.

FIG. 6 is a front elevational view of a second embodiment of my new design, the bottom housing being identical to that of the first embodiment.

FIG. 7 is a top plan view thereof.
